UNITED STATES PATENT OFFICE

JAMES C. HOBBS, OF PAINESVILLE, OHIO

TUBE FOR FURNACES

Application filed October 20, 1926, Serial No. 142,796. Renewed April 5, 1932.

This invention relates to tubes that may have liquid passing through them and be used as slag screen tubes in a furnace, or as furnace wall cooling tubes, and will be understood from the description in connection with the accompanying drawings, in which Fig. 1 is a vertical section through a boiler furnace illustrating how the tubes may be installed; Fig. 2 is a section through one of the tubes and a portion of a header; Fig. 3 is an end view of the tube; Fig. 4 is a section, partly broken away, showing a different embodiment of the invention; Fig. 5 is a similar view taken at right-angles to Fig. 4, and Fig. 6 is an end view of the tube shown in Figs. 4 and 5.

Heretofore, in attempting to use water tubes that are connected to the water circulating system of a boiler as furnace wall cooling tubes or as water screen tubes, difficulties have arisen because of the tubes burning, due to the fact that water is not directed against those sides of the tubes exposed to the highest temperatures. This difficulty is especially noticeable in horizontal water screen tubes located near the bottom of the furnace, as the tendency of the steam to rise in such tubes prevents the water from keeping the upper side of the inside of such tubes wet. The invention will be particularly described in connection with water tube boilers but it is to be understood that it is useful in other places, such as oil stills, for example, where tubes are in danger of being burned out because the liquid flowing through the tubes is not kept in contact with the inside wall of the tube adjacent the places where intense heat strikes the outside of the tubes.

In the accompanying drawings, reference characters 10 and 11 indicate the front and rear walls, respectively, of a furnace that may be provided with a fuel burner 12 near the top on the front side thereof. A boiler, the water tubes of which are shown at 13, may be located above the furnace and receive heat therefrom. The side wall cooling tubes 14 of the furnace may be connected to the water circulating system of the boiler through headers 15 and 16 and pipes 17 and 18 in the well-known manner. Pipe 17 may also be

connected to the header 19 from which water screen tubes 20 extend through the front wall 10 of the furnace across the lower portion of the furnace, and through the rear wall 11 thereof, and are connected by elbows 21 to the rear furnace wall cooling tubes 22 which are, in turn, connected to a header 23 and thence to the boiler.

In order to keep the inside of the tubes wet and thus prevent the same from being burned out, the tubes may be provided with means for causing the water passing therethrough to partake of a rotary motion or to follow a spiral path through the tubes. In the embodiment shown in Figs. 2 and 3, a spiral strip 25 is shown for this purpose in one of the horizontal tubes 20. The end 26 of this strip is anchored in a flanged ring 27 that is inserted into the end of the tube 20 and keeps the strip in place. This strip extends into the tube a short distance from the header 19 and serves to give the water a whirling motion as it passes through the tube 20, thus causing the water to flow along the inside wall of the tube in a spiral path and keep the same wet. When this spiral strip is located in the cool end of the tube, as shown, very little, if any, steam will be formed in the water before it passes beyond the end of the spiral strip 25. The strip may, however, extend any desired distance into tube.

In the form shown in Figs. 2 and 3 the spiral is cut away, as shown at 28, at each turn along the upper side, so that steam can pass longitudinally through the tube without following the spiral path, while the water itself is caused to follow the spiral path and keep the inside of the tube wet, even along its upper portion, or along the side next to the furnace. Under those conditions, the first action which takes place in the circulating system is a convection flow of water. If, as is sometimes the case, the starting is slow, there comes a time when the convection flow may stop altogether, due to the water throughout the system being at the same temperature. However this situation would not prevail for any great length of time due to the application of heat to the upper sides

of the horizontally inclined tubes which would cause a certain amount of steam bubbles to be formed and as these accumulate in the top parts of the tubes and there is not sufficient flow to carry them into the uptake part of the system, the tubes are in danger of being burned out. The straight uninterrupted path is therefore provided through which the steam bubbles which may be trapped in the top of the tubes may more easily flow through the uptake part of the system and in this manner promote a rapid circulation through the system which is to be desired. When the rapid circulation is attained the deflection vanes in the tube cause the water flowing therethrough to adopt a rotating path so that while the application of heat to the upper surface of the tube will tend to cause steam bubbles to accumulate there, the rotating water will sweep such steam bubbles away and thereby obviate any danger of the tubes being burned out.

In the embodiment shown in Figs. 4, 5 and 6, a rod 30 extends through the tube 20 and is held at both ends by means of the straps 31 that extend across the tube, the rod 30 being threaded at both ends so that nuts 32 may retain the same in place by being screwed up against the straps 31. In this form deflector plates 33 are attached to the lower side of the rod 30 as by spot-welding, as indicated at 34, these deflector plates being disposed at an angle to the axis of the tube, so that the water will be caused to partake of a circular or rotary motion to keep the entire inside of the tube wet while it is passing therethrough. At the same time, the steam can pass longitudinally through the upper half of the tube without being deflected by the deflector plates 33.

It will be noticed that spiral strips or deflector plates not only serve to cause the water to keep the entire insides of the tubes wet, but these strips and plates also serve the purpose of aiding the distribution of the water through the tubes from the headers, since they interpose resistances which help to prevent any single tube from having too much water pass therethrough. The spiral strips or deflector plates may be located not only in the slag screen tubes in the bottom of the furnace, but also in the wall cooling tubes along the sides of the furnace.

Various modifications and changes may be made without departing from the spirit or scope of this invention.

I claim:

1. In a steam and water circulating system, a horizontally arranged tube having its upper portion exposed to a source of heat, and deflecting vanes in the tube constructed to cause the water in the tube to rotate, said vanes being spaced from the wall of the tube at said upper portion.
2. In a steam and water circulating sys-

tem, a horizontally arranged tube having its upper portion exposed to a source of heat, and deflecting vanes in the tube constructed to cause the water in the tube to rotate, said vanes having their upper portions removed 70 and having their lower portions inclined to the direction of flow through the tube.

3. In a steam and water circulating system, a horizontally arranged tube having its upper portion exposed to a source of heat, 75 and means in the tube to cause the water to rotate therein during its passage therethrough, said means leaving a space at the said upper portion of the tube.
